This is a continuation-in-part of design application Ser. No. 3,423, filed on Aug. 11, 1966, and now abandoned.

FIG. 1 is a perspective view of the fireplace grate embodying my new design, the repetitive grating pattern and end strip being partially shown for convenience of illustration.

FIG. 2 is an end view thereof.

FIG. 3 is a partial plan view of the fireplace grate design, taken at substantially the center of FIG. 1;

FIG. 4 is a fragmentary cross-sectional view taken along line 4—4 of FIG. 3.

FIG. 5 is a full front view of the fireplace grate design in accordance with this invention;

FIG. 6 is a full end view of the fireplace grate design shown in FIG. 5;

FIG. 7 is a full plan view of the fireplace grate design shown in FIG. 5.

I claim:

The ornamental design for a fireplace grate, substantially as shown and described.
